UNITED STATES PATENT OFFICE.

WILLIAM J. PARKER, OF ST. LOUIS, MISSOURI.

SAFETY DEVICE FOR PUNCH-PRESSES.

1,184,010.

Specification of Letters Patent. Patented May 23, 1916.

Application filed August 17, 1914. Serial No. 857,007.

To all whom it may concern:

Be it known that I, WILLIAM J. PARKER, a citizen of the United States, and residing at St. Louis, in the State of Missouri, have 5 invented a certain new and useful Improvement in Safety Devices for Punch-Presses and the like, of which the following is a specification.

This invention relates to safety devices, 10 and more particularly, to safety devices for punch presses.

In the operation of punch presses, the work must be inserted between the punch and the die by the operator, and many accidents are caused by the inadvertent operation of the punch while the operator's hand is between the punch and die. Many safety devices have been proposed to prevent such accidents, but they have not been entirely 15 successful. In some classes of safety devices, a guard moves between the punch and die and the operator, and such a guard has generally been moved downwardly with the punch. Such operation of the guard would 20 cause the operator's hand to become caught by the guard moving down on it, thereby holding it in position and causing, in itself, injury.

The objects of this invention, therefore, 25 are to devise a safety device for punch presses, in which a guard moves in such a manner as to move the operator's hand or hands out of the way.

Further objects will appear from the detail description taken in connection with the accompanying drawing, in which:

Figure 1 is a front elevation of a punch press, showing one embodiment of this invention; Fig. 2 is a side elevation; Fig. 3 is 40 an enlarged section on the line 3—3, Fig. 1; Fig. 4 is an enlarged section on the line 4—4, Fig. 1; and, Fig. 5 is a detail plan view, showing another embodiment of this invention.

Referring to the accompanying drawing, and more particularly, to Figs. 1 to 4 inclusive, 45 10 designates the base and 11 the frame of a punch press of well known construction. The frame supports a platen 12, and has a guide for a ram 13 operated from the drive shaft 14. A die 15 is mounted upon the platen, while a coöperating punch 16 is mounted on the ram. The parts described may be of usual construction, and further description is, therefore, unneces-

sary. A bracket 17 is attached to the frame 11 in any suitable manner, as by screws or bolts 18, and this bracket is provided with an elongated forwardly extending bearing 19. A hollow shaft 20 is mounted in this bearing, and is supported against endwise movement by an arm 21 and a collar 22, both clamped to the shaft by means of suitable screws arranged flush therewith. The arm 21, which rotates with the shaft, has pivoted thereto a threaded link 23 passing through a head 24 on a bracket 25 bolted to the rear face of the ram 13. The link has threaded thereon nuts 26 engaging the opposite faces of the head 24. The shaft 20 has mounted therein a shank 27 secured in position by a set screw 28, and having an arm 29 arranged in front of and below the die 15 mounted on the platen. A sector-shaped curtain 30, of canvas, or any other suitable material, is attached to the platen and to the arm 29. The connection between the ram and the arm 29 causes this arm to move upwardly from full to dotted line position when the ram moves downwardly to punch the material. It will also be noted that, in view of the pivotal mounting of the arm to one side of the die, this arm will move laterally, as well as upwardly. As the arm moves upwardly, the canvas curtain 30 will move in front of the punch and die so as to obstruct the same. The arm 29, which forms the guard of the safety device, is normally positioned in front of and below the level of the die. The curtain 30 is also normally folded up or collapsed while the arm is down.

In the operation of a machine, the operator will insert the work between the punch and die, and will then usually withdraw his hand before he starts the machine. If, however, he should neglect to withdraw his hand, then the upwardly and laterally moving guard will lift his hand or hands out of the way, so that they cannot be caught by the punch as it descends. In view of the fact that the guard has a compound upward and lateral movement, the hands will be moved laterally, as well as upwardly. The movement of the guard operating on the arm or hand of the operator, positioned in front of the machine, will naturally be such as to cause the hand or hands to be withdrawn away from the punch. This result is brought about by moving the guard in a di-

rection opposite to the direction of movement of the punch. As the guard moves upwardly, the canvas curtain 30 will move between the punch and die and the operator, 5 so as to entirely obstruct the punch and die until the punch again ascends. This will prevent the operator from placing his hands under the punch until it is safe to do so. The device can be applied to any punch 10 press, as the adjustment of the screws 26 on the link 23, and the adjustment of the shank 27 longitudinally of the shaft 20, will permit application of the device to punch presses of different sizes.

15 In the construction shown in Fig. 5, the arm 29 is arranged at an obtuse angle with respect to the shank 27, while the axis of the bearing 19 is arranged at an obtuse angle with respect to a line drawn parallel to the 20 front of the machine. This construction causes the end of the arm 29 to move forwardly, as well as upwardly and laterally, and thus causes the hands of the operator to be moved forwardly, or away from the 25 punch and die, as well as upwardly and laterally.

It is obvious that various changes may be made in details of construction without departing from the spirit of this invention, 30 and it is, therefore, to be understood that this invention is not to be limited to the specific construction shown and described.

Having thus described the invention, what is claimed is:

1. In a punch press having a punch carrying ram and die, a safety device having a front guard between the operator and punch, and operative connections between said ram and guard for moving the latter in a direction opposite to the movement of the punch and laterally thereof. 35
2. In a punch press having a punch carrying ram and die, a safety device having a guard in front of and normally below the level of the die, and means connected with 40 and operated by said ram for moving said guard upwardly and laterally relative to the die. 45
3. In a punch press having a punch carrying ram and die, a safety device having a guard in front of the punch and die, operative connections between the ram and guard for moving the latter in a direction opposite to the movement of the punch and laterally thereof, and a curtain movable 50 with said guard in front of said punch and die. 55

In testimony whereof I affix my signature in the presence of these two witnesses.

WILLIAM J. PARKER.
